(57) **CLAIM**

The ornamental design for a nozzle for hair dryer as shown and described.

DESCRIPTION

1. Nozzle for hair dryer

1.1 : Front perspective view

1.2 : Front view

1.3 : Back view

1.4 : Left view

1.5 : Top view

1.6 : Back perspective view

1.7 : Front perspective view 2

Reproduction 1.4 is a left view of the claimed design where the right view is a mirror image; reproduction 1.5 is a top view thereof where the bottom view is a mirror image; and reproduction 1.7 is a front perspective view showing the use state that the claimed design is combined with a hair dryer. The broken lines shown in reproductions 1.2 and 1.3 illustrate portions of the nozzle for hair dryer which form no part of the claimed design. The broken lines shown in reproduction 1.7 illustrate portions of the nozzle for hair dryer which form no part of the claimed design.

(Continued)

tion 1.7 illustrating a hair dryer illustrate environmental subject matter that forms no part of the claimed design.

1 Claim, 7 Drawing Sheets
